UNITED STATES PATENT OFFICE

2,495,446

BUTTON DIPPING AND DRYING MACHINE

Bernard C. Eisenberg, Brooklyn, N. Y.

Application February 26, 1948, Serial No. 11,269

2 Claims. (CL. 91—46)

1

My invention relates to the art of making buttons and, more particularly, to machines for dipping and drying buttons.

According to known methods, buttons are dipped into liquid. For example, buttons made of plastics soluble in acetone are dipped in acetone in order to provide these buttons with luster and with a smooth and hard surface. In other cases, buttons are colored or coated by a liquid treatment. Hitherto, the buttons have been inserted into and have been removed from the liquid bath by hand. Objects of my invention are to save labor, to carry out the dipping operation mechanically or automatically, to treat a large quantity of buttons in relatively short time, and to provide a dipping treatment that affects all these buttons in accurately uniform manner.

Other objects are to move the buttons in the bath, to adjust the length of the way over which the buttons move in the bath, and thereby to adjust the duration of the liquid treatment.

Further objects are to dry the buttons after the liquid treatment, to transport the buttons from the bath into a drying chamber mechanically or automatically, to move the buttons into and through the drying chamber by the same carrying element which carried the buttons through the bath, and to guide the buttons in the drying chamber along a repeatedly bending or snake-like path whereby the buttons remain in the drying chamber for a considerable length of time.

Still other objects are to combine a button dipping machine with a button shanking machine, to pick up buttons after the shanking operation automatically by the carrying element which carries the buttons through the bath and the drying chamber, and to avoid manual handling of the buttons throughout the shanking, dipping and drying operations.

Still further objects are to attain these results with simple and reliable means, and with a machine that can be easily made, operated and maintained and that can be adjusted for buttons of different types or dimensions.

Still other objects and advantages will appear from the following description of an exemplifying embodiment of my invention, from the appended claims and from the accompanying drawing in which:

Fig. 1 shows a front view of an illustrative embodiment of my invention.

Fig. 2 shows a cross-section taken along the broken line 2—2 in Fig. 1.

Fig. 3 shows a cross-section taken along the line 3—3 in Fig. 1.

2

Fig. 4 shows a view of some parts of this embodiment, seen from the left side in Fig. 2 or from the back side in Fig. 1, some of the represented parts being broken off.

5 Fig. 5 shows a cross-section taken along the line 5—5 in Fig. 1, the lower part of the machine being broken off.

Fig. 6 shows a perspective view of a detail of the same embodiment, a portion of this detail being broken off.

Fig. 7 shows a cross-section taken along the line 7—7 in Fig. 1.

Fig. 8 shows a cross-section taken along the broken line 8—8 in Fig. 1.

15 Fig. 9 shows a top view of a detail of the same embodiment, comprising a finger, a broken off portion of a chain moving this finger, and a broken off portion of a table underlying this finger.

20 Fig. 10 shows a front view of the chain portion and of the finger shown in Fig. 9.

Fig. 11 shows a top view of another detail, comprising a chain portion and a pick-up member attached to this chain portion.

25 Fig. 12 shows a front view of the parts shown in Fig. 11.

Fig. 13 shows still another detail, comprising a chain portion and a carrying member attached to this chain portion.

30 Fig. 14 shows a front view of the parts shown in Fig. 13.

Fig. 15 shows a part of the cross-section shown in Fig. 5, represented on a larger scale.

Fig. 6 and Figs. 9 to 15 are represented on 35 about true scale. Figs. 2, 4 and 5 are represented on a reduced scale. Figs. 1, 3, 7 and 8 are represented on a still more reduced scale. In the figures represented on reduced scales, some parts are represented in simplified shapes and some other parts are omitted for the sake of clearer representation of the embodiment.

40 Referring to the drawings, numeral 1 indicates a trough or receptacle. This receptacle may have an elongated shape and an open upper side and may be filled with a liquid suitable for treating buttons, for example, with acetone or dye. This liquid may fill the receptacle as far as near to the receptacle's upper rim, for example up to a level

45 50 Two rotatable shafts 6 and 9 cross the receptacle 1 horizontally. The shaft 6 is positioned near that end of the receptacle which is at the right side in Fig. 1, and carries a wheel 10. The shaft 9 is positioned near the opposite end of the

55 receptacle and carries two wheels 11 and 12.

A frame comprising a back wall 13 and front walls 14 and 15 is positioned on top of the receptacle 1. The walls 14 and 15 are connected by cross-walls which will be described later and by a horizontal plate 16. This plate projects beyond the front walls and serves as a base for a shank feeding and cutting device 17 of that type which has been described and shown in my co-pending patent application of December 23, 1947, Ser. No. 793,346. A plate-shaped table 18 extends horizontally from the back wall 13 to the front and has a longitudinal slot 19 running parallel to the back wall and communicating with a broader recess 20 provided near that end of the table which is at the right side in Fig. 1.

In accordance with the mentioned prior application, the shank cutting and feeding device 17 comprises a rotatable shaft 21, a wheel 22 carried by the shaft 21, a knife 23 and a device 24 for the application of an adhesive making liquid to the shanks.

A shaft 25 is rotatably carried by a block 26 slidable in a window or slot 27 of the front wall 14 and carries a wheel 28. The block 26 can be adjusted by means of a screw 29 passing through a threaded hole of a vertical cross-wall 30 into a space accessible through a recess 31 of the front wall 14. The outer end of the screw 29 is provided with a hand wheel 32.

A shaft 33 is rotatable in bores of the back wall 13 and of the front wall 14 and carries two adjacent wheels 34 and 35. Only one of these wheels, for example, the wheel 34, is directly affixed to the shaft 33. The other wheel is coupled with the affixed wheel whereby both wheels 34 and 35 rotate with the shaft 33. The position of the wheel 35 with respect to the wheel 34 is adjustable in the turning direction. For example, two bolts 36 are affixed to the wheel 34, pass through arc-shaped slots 37 of the wheel 35 and have ends engaged by nuts 38. The relative adjustment of the wheels 34 and 35 is facilitated by a bolt 39 provided with screw threads 40 and 41 winding in opposite directions and engaging correspondingly wound threads in two plates 42 and 43. The plate 42 is affixed to the wheel 35. The plate 43 is connected to the wheel 34 by a pin 44 passing through an arc-shaped slot 45 of the wheel 35. The distance between the plates 42 and 43, and thereby the angular relative position of the wheels 34 and 35, varies when the bolt 39 is turned.

The wheels 28 and 34 are connected by an endless flexible element 46 which may be a chain consisting of links 47 (Figs. 9 and 10). Transport members 48 are affixed to some of these links and distributed at equal intervals over the length of the element 46. The members 48 are omitted in Figs. 1 and 7 and, partly, in Figs. 2 and 5. As to be seen from Figs. 9 and 15, the members 48 form fingers sliding over the table 18 and having V-shaped recesses positioned symmetrically with respect to the slot 19. Thereby, each member or finger 48 is adapted to move or shift a button 49 inserted in the recess along the table 18 so that the center of the button moves over and along the slot 19.

The wheel 35 is connected with a wheel 50 by a flexible element or chain 51 which is guided over another wheel 52 so that the wheels 35 and 50 rotate in opposite directions. The wheel 50 is affixed to a shaft 53, and the wheel 52 to a shaft 54. The shafts 53 and 54 are rotatable in bores of the back wall 13 and of the front wall 15. Another wheel 55 is affixed to the shaft 53.

A flexible endless element 56 engages the wheel 55 and runs from the latter wheel to the wheel 10 and further along the receptacle 1 to the wheel 11. From the wheel 11, the element 56 runs in the risingly inclined direction of the arrow 57 (Fig. 1) to an adjustable wheel 58 and returns in the reverse direction of the arrow 59 to the wheel 12. Therefrom, the element 56 runs in the direction of the arrow 60 and enters a drying chamber 61 through a bottom opening 62 of the latter. The element 56 leaves the chamber 61 through another bottom opening 63 and runs in the direction of the arrow 64 to a wheel 65 and further to a wheel 66 from which the element returns over a wheel 67 to the wheel 55. Thus, the element 56 extends and moves along a circularly returning path. This path runs through the receptacle 1 so that buttons 49 carried by the element 56 in a manner which will be described later move through the liquid contained in the receptacle (see Fig. 2). These buttons move along a path parallel to that of the element 56. The path of the buttons running from the wheel 10 to the wheel 11 is completely submerged while the inclined portions running in the directions of the arrows 57 and 59 may be more or less submerged according to the adjustment of the wheel 58 which can be shifted vertically, for example, by the following means:

30 A shaft 68 carries the wheel 58 and is rotatable in bores of a fork 69. This fork has a front extension 70 slidable in a vertical slot 71 of the front wall 15. A vertical screw bolt 72 passes through a correspondingly threaded hole in the extension 70, has a cylindrical zone rotatable in a bore of a front extension 73 of the front wall 15 and has a square head 74. When this head is turned, the screw 72 moves the extension 70, the fork 69 and the wheel 58 in vertical direction. 40 The wheels 65, 66 and 67 are carried, respectively, by shafts 75, 76 and 77 which are rotatable in bores of the back wall 13 and of the front wall 15. Between the wheels 67 and 55, the element 56 may be additionally guided by a track 78 having a substantially horizontal upper surface over which this element or blocks 93 affixed to this element slide. The track 78 is supported by a horizontal cross-wall 79 and may be adjustably connected to this cross-wall by screw bolts 80 provided with nuts 81 visible best in Fig. 5.

The drying chamber 61 may have any known and suitable structure, may be positioned on top of an extension 82 of the back wall 13 and of a slightly forwardly projecting extension 83 of the front wall 15, and is situated over that end of the receptacle 1 which contains the wheels 11 and 12. Four parallel and rotatable shafts 84, 85, 86 and 87 cross the drying chamber horizontally. Each of these shafts carries wheels which serve to 60 guide the element 56 in the chamber along a snake-like winding path. For example, each of the shafts 84, 85 and 86 carries four wheels 88, 89, 90 and 91 while the shaft 87 carries one wheel less, that is, wheels 89, 90 and 91. The snake-like path runs from the opening 62 over wheel 88 on shaft 84 up to wheel 88 on shaft 85, then down in slightly oblique direction to wheel 89 on shaft 84, up to wheel 89 on shaft 85, down to wheel 90 on shaft 84 and so on, over the remaining wheels on shafts 84 and 85. From the last of these wheels, wheel 91 on shaft 85, the path of the element 56 runs horizontally to wheel 91 on shaft 86, then down to wheel 91 on shaft 87, up in slightly oblique direction to wheel 90 on shaft 86 and so on, over the remaining wheels

on shafts 86 and 87. From the last of these wheels, wheel 88 on shaft 86, the path runs to the opening 63 and further as described before.

The flexible element 56 is preferably constituted by a chain similar to the chain 46 and composed of links 92 (Figs. 11 and 12). Blocks or members 93 are affixed to some of these links and distributed at equal intervals over the entire length of the element 56. These intervals are equal to the intervals of the fingers or transport members 48. Each block 93 is provided with a needle 94 which points in a direction crossing the moving direction of the element 56 and of the blocks 93 or laterally with respect to their path. The blocks 93 and the needles 94 are omitted in Figs. 1, 3, 7, 8 and partly in Fig. 2 for the sake of clear representation of these figures. As to be seen in Fig. 15, the needles 94 are so long and so positioned that each needle reaches through the slot 18 of the table 18 when the block 93 or that part of the element 56 which carries the needle slides over the track 78. Thereby, each needle enters a button 49 which, at the same time, is moved by a finger 48 over and along the slot 19 and parallel to the element 56.

The path of the element 56 has a portion 95 positioned in the moving direction before the horizontal surface of the track 78 and gradually approaching the path of the element 46. Thereby, these two paths converge, and needles running along the approaching pass pick into buttons. Thereafter, the picked up buttons are held by the needles and are carried by the same along the path of the element 56 until the buttons are separated from the needles as will be described later.

The buttons are prevented from evading the picking needles upwardly by a shoe 96 positioned over the track 78 at a suitable distance over the table 18. This distance is adjustable by means of a hand wheel 97 to which a bolt 98 is affixed. The lower end of this bolt is anchored in the shoe 96. The bolt 98 has a screw thread. The threaded part of this bolt passes through a correspondingly threaded bore of a cross-wall 99. The shoe 96 may be slidably guided in vertical direction in an opening of another cross-wall 100.

The picked up buttons are detached or stripped from the needles before the needles return to the approaching portion 95 of their path. This is preferably done by a trap 101 contacting each button shortly before the same leaves the drying chamber 61. The button trap 101 comprises a fork 102 rising in oblique direction into the path of the needles 94 and of the buttons held by the needles. This fork has a slot sufficiently broad for the passage of the needles, but not broad enough for the passage of the buttons. The fork 102 leads to a chute or channel 103 forming the lower part of the trap 101 and passing through the wall of the drying chamber. When a needle 94 passes through the fork 102, this fork retains the button whereupon the detached button drops through the chute 103 into the open.

The buttons discarded in this manner are provided with smooth, hard and brilliant or colored surfaces, due to the preceding treatment in the receptacle 1 and in the drying chamber 61. These treatments may be used also to solidify or to strengthen the connection between buttons and their shanks, especially if the buttons have been shanked by a button shanking machine according to the mentioned prior patent application. In this case, further advantages are obtained by in-

corporating the shanking machine in the dipping and drying machine.

The slotted table 18, the fingers 48, the chain 46 and the means for guidance and adjustment of the latter element, described before with reference to numerals 25 to 45 are so arranged that they serve both the dipping and the shanking mechanisms of the combined machine. In addition to these common parts and to the parts 16, 17 and 21 to 24, the shanking mechanism comprises a shoe 104 similar to the shoe 96 and adjustable by a handwheel 105 similar to the handwheel 97, and a flexible element or chain 106 extending and movable along a circularly returning path. This path runs over the wheel 22, two other wheels 107 and 108 and a track 109 positioned between the two latter wheels. Transport members or carriers 110 (Figs. 13 and 14) are affixed to the chain 106 at intervals equal to the intervals of the fingers 48. The structures, arrangements and functions of all these parts of the shanking mechanism are substantially the same as those of the corresponding parts of the shanking machine shown and described in the mentioned prior application, except that the table 48 guides the shanked buttons farther to the right side in Fig. 1 where these buttons are picked by the needles 94.

The elements 46, 56 and 106 and the parts affixed to the same move with the same speed. This result may be obtained by suitable diameters of the wheels transmitting movement or speed from one element to another at the ratio one to one. For example, the co-axial wheels 34 and 35 have equal diameters, and the co-axial wheels 50 and 55 have equal diameters whereby the elements 46 and 56 move with the speed of the connecting chain 51. The same speed may be transmitted to the element 106 by a driving connection between one of the chains 46 or 56 and the chain 106. For example, the shaft 111 of the wheel 108 carries another wheel 112, and the shaft 77 of the wheel 67 carries another wheel 113. The ratio of the diameters of the co-axial wheels 108 and 112 is the same as the ratio of the diameters of the co-axial wheels 67 and 113; and the wheels 112 and 113 are connected by an endless chain or flexible element 114.

The relative longitudinal positions of the elements 56 and 106 are preferably adjustable whereby an accurate co-ordination between the shanking and the pick-up positions of the buttons can be secured. For this purpose, one of the wheels 108 and 112 may be not directly affixed to the shaft 111, but may be adjustably connected to the other wheel in the same manner as the wheel 35 is connected to the wheel 34.

As appears from the foregoing description, all wheels and flexible elements or chains are interconnected by driving means whereby each of these wheels or elements may derive motion from any of the other wheels or elements. The entire machine may be driven by a motor of any known and suitable type which may act on the shaft of any of the wheels described.

The machine is operated as follows:

The shoes 96 and 104 are adjusted so that their distance from the table 18 is equal to the height of the buttons 49. The relative angular position 70 of the wheels 34 and 35 is adjusted in the manner described until a button 49 moved by a finger 48 is located in pick-up position over a needle 94. The relative angular position of the wheels 108 and 112 is so adjusted that a button having the 75 correct shanking position over the track 109 later

has the correct pick-up position over the track 18.

Then, the machine is started and buttons are placed on the table 18 before the fingers 48 in the same manner as described in my mentioned prior application. These buttons are moved from left to right in Fig. 1 and may be shanked while passing over the track 109 in the manner described in this prior application. Then, the buttons are picked by the needles 94 and carried through the receptacle 1 and the drying chamber 61 in the manner described before.

I desire it understood that my invention is not confined to the particular embodiment shown and described, the same being merely illustrative, and that my invention may be carried out in other ways without departing from the spirit of my invention as it is obvious that the particular embodiment shown and described is only one of the many that may be employed to attain the objects of my invention.

Having described the nature of my invention, what I claim and desire to protect by Letters Patent is:

1. A button dipping machine comprising a receptacle adapted to be filled with a button treating liquid, a flexible element extending and movable along a circularly returning path running through said receptacle, a series of needles affixed to said element, pointing laterally with respect to said path and being adapted to pick and hold buttons, a table with a slot, another flexible element extending and movable along a circularly returning path having a portion running over said table parallel to said slot, and a series of fingers affixed to said other element and adapted to shift buttons over a slotted part of said table, said fingers having V-shaped recesses for the

insertion of said buttons, the path of said first element having a portion approaching said slotted part from the lower side so that needles reach through said slot into the path of said buttons.

2. A button dipping machine comprising a receptacle adapted to be filled with a button treating liquid, a flexible element extending and movable along a circularly returning path running through said receptacle, a series of needles affixed to said element, pointing laterally with respect to said path and being adapted to pick and hold buttons, a table with a slot, a shoe positioned over said slot at an adjustable distance from said table, another flexible element extending and movable along a circularly returning path having a portion running over said table parallel to said slot, and a series of fingers affixed to said other element and adapted to shift buttons under said shoe over a slotted part of said table, the path of said first element having a portion approaching said slotted part from the lower side so that needles reach through said slot into the path of said buttons.
